US00D962410S

(12) **United States Design Patent** (10) Patent No.: **US D962,410 S**
 (45) Date of Patent: **** Aug. 30, 2022**

(54) **AIR PURIFIER**

(71) Applicants: **BEIJING XIAOMI MOBILE SOFTWARE CO., LTD.**, Beijing (CN); **Beijing Smartmi Technology Co., Ltd.**, Beijing (CN)

(72) Inventors: **Guang Xi**, Beijing (CN); **Song Yu**, Beijing (CN)

(73) Assignees: **BEIJING XIAOMI MOBILE SOFTWARE CO., LTD.**, Beijing (CN); **BEIJING SMARTMI TECHNOLOGY CO., LTD.**, Beijing (CN)

(**) Term: **15 Years**

(21) Appl. No.: **29/770,285**

(22) Filed: **Feb. 10, 2021**

(30) **Foreign Application Priority Data**
